UNITED STATES PATENT OFFICE.

RUDOLPH HOFFMAN, OF KANKAKEE, ILLINOIS, ASSIGNEE TO SEARS, ROEBUCK AND COMPANY, OF CHICAGO, ILLINOIS, A CORPORATION OF NEW YORK.

OIL-STOVE.

1,188,782.

Specification of Letters Patent. Patented June 27, 1916.

Application filed March 23, 1916. Serial No. 86,085.

To all whom it may concern:

Be it known that I, RUDOLPH HOFFMAN, a citizen of the United States, residing at Kankakee, in the county of Kankakee and State of Illinois, have invented certain new and useful Improvements in Oil-Stoves, of which the following is a specification.

This invention relates particularly to oil stoves of the so-called wickless type. In such stoves each burner comprises a relatively shallow bowl or trough containing a quantity of oil. The trough is supplied with oil from a well or receptacle in which the oil is maintained at a certain level. If, therefore, the level of oil in the trough is to be at the right height, the trough must be properly located with reference to the well. Usually two or more troughs located side by side are supplied from a single well by means of a feed pipe extending from the well to the troughs. It will be evident that if the stove is placed upon a floor which is not horizontal, the oil will stand at different levels in the several troughs.

The object of this invention is to provide convenient, self-locking means for adjusting the troughs into horizontal position and thus compensate for any lack of horizontality of the floor or other surface on which the stove is set.

In the accompanying drawings, Figure 1 is a fragmental front elevation of a wickless oil stove embodying the features of my invention. Fig. 2 is a vertical sectional view of the adjusting means, taken in the plane of dotted line 2-2 of Fig. 3. Fig. 3 is a view taken from the right-hand side of Fig. 2.

While the invention may be embodied in stoves of any preferred construction, I have herein shown a stove having three burners A of the wickless blue-flame oil-fuel type. Each burner comprises a bowl or trough 1 similar to the one shown in Patent No. 1,154,637, dated September 28, 1915. The troughs are supported upon and communicate with a feed pipe 2 which is connected at one end with a well or oil receptacle 3. Upon the well 3 is a font or reservoir 4 the

outlet to which is sealed or unsealed by the 50 rise or fall of the oil-level in the well 3. Adjacent to the well 3 the feed pipe passes freely through, and is supported within, an opening in the wall or framework of the stove. The end of the feed pipe opposite 55 to the well is closed and is supported for vertical adjustment. The end wall 5 has a vertically elongated opening 6 through which the feed pipe extends freely.

7 is a plate having a circular opening 8 60 in which the feed pipe is supported. The plate 7 is secured to the end wall 5 by means of a bolt 9 extending through the end wall and through a slot 10 in the plate 7. 11 is a nut on the bolt. The slot 10 is curved upon 65 the arc of a circle which is eccentric to the opening 8. 12 is a handle on the plate 7. It will be seen that as the plate 7 is turned the adjacent end of the feed pipe will be raised or lowered.

If after the stove has been set in the desired place, it is found that the oil level varies in the troughs 1, the nut 11 is loosened, the plate 7 is turned to raise or lower the adjacent end of the feed pipe until 75 the oil stands at the same level in all the troughs, and the nut again tightened. It will be evident that the weight of the feed pipe and the several burners is supported by the top wall of the slot 10 resting upon the 80 bolt 9. As this wall approximates a horizontal surface, it will be seen that considerable resistance is offered to downward movement of the feed pipe, so that even if the nut 11 were left loose, there is security against 85 accidental dropping of the burners.

I claim as my invention:

1. A stove having, in combination, a stationary reservoir, a feed pipe connected at one end to the reservoir, a burner supported upon the feed-pipe, an end wall having a vertically elongated opening through which the feed-pipe extends, a pipe-supporting member having a circular opening through which the feed-pipe extends, said member having a slot, different portions of the slot being at different distances from the opening in said member, a supporting

member on the end wall and extending through the slot, and a handle portion on the first mentioned member.

2. A stove having, in combination, a feed-pipe, a burner supported upon the feed-pipe, a member having an opening in which the feed-pipe is supported, said member having

a curved slot above the opening, different portions of said slot being at different distances from said opening, and a supporting member passing through said slot.

In testimony whereof, I have hereunto set my hand.

RUDOLPH HOFFMAN.
